UNITED STATES PATENT OFFICE.

JOHN T. WOOLSEY, OF KANSAS CITY, KANSAS.

PRECIPITATOR.

1,182,956.

Specification of Letters Patent. Patented May 16, 1916.

Application filed June 7, 1915. Serial No. 32,635.

To all whom it may concern:

Be it known that I, JOHN T. WOOLSEY, a citizen of the United States, residing at Kansas City, in the county of Wyandotte 5 and State of Kansas, have invented certain new and useful Improvements in Precipitators, of which the following is a full, clear, and exact description, such as will enable others skilled in the art to which it appertains to make and use the same.

The invention relates to precipitators for separating the sediment and foreign substance from water thermosto siphoned from a steam generator and seeks to provide an improved precipitator which may be connected with and receive water through a skimmer contained in a steam generator for the purpose of precipitating the sediment from and returning the water to the generator by thermosto siphon circulation.

It is essential that precipitators be constructed with as few joints as possible and that these be perfectly tight, also that the water be required to follow a circuitous 25 route while exposed to the action of precipitation so that as near as practically possible all the water will be subjected to the separating action for an even space of time, and some means of easily and quickly 30 removing the sediment is very advantageous.

The present invention seeks to provide an improved precipitator with a single joint in the body portion, an improved means of 35 establishing a circuit within the precipitator, and a novel and practical means of discharging the sediment when collected.

With these and other objects in view, the invention consists in the features of improved construction, shapes, combinations 40 and arrangements of parts hereinafter set forth illustrated in the accompanying drawings and more particularly pointed out in the claims hereunto appended.

In the drawings:—Figure 1 is a view in elevation of the improved precipitator connected to a steam generator and to a skimmer within the generator, a portion of the latter being broken away to illustrate the 45 connections. Fig. 2 is a view of the precipitator in vertical section, taken on line a—a of Fig. 3. Fig. 3 is an inverted plan view of the upper portion of the shell of the precipitator. Fig. 4 is a plan view of the lower 50 portion of the shell of the precipitator and of the sediment removing cone.

The steam generator 1, is of common and well known construction and is shown merely to illustrate the connection and action of the precipitator; the generator being broken away for the same purpose and to show the skimmer 2, which is no part of the present invention. The lower section 3 of the precipitator shell has the shape of one half of a sphere, is hollow and is provided with the radially projecting flange 4, around the largest diameter thereof, which is the upward face, the latter face having a recess 5 around the inner edge of its diameter to receive the gasket 6. Projecting inwardly from the upward face of the shell section 3 are three lugs on which rests the cone 7, the latter being preferably riveted to the lugs as shown. Around the section 3 immediately underneath the flange 4 are the lugs 8 from which project downwardly the legs 9, upon which rests the entire weight of the precipitator and immediate connections. Upon the gasket 6 rests the upper section 10 of the precipitator shell, which is cylindrical and extends upward and is closed at the upper end by a spherically shaped head 11 integral with the shell, there being two hubs or bosses 12 and 13 projecting in opposite direction from the head, 85 both of which are threaded to receive lengths of pipe to connect to the steam generator, the boss 12 accommodating the intake and the boss 13 the discharge pipes of the precipitator. The lower end of the shell 90 section 10 is provided with the radically projecting flange 14 which is a companion to the flange 4, and bolts 15 pass through both flanges and draw the upper and lower sections of the shell tight upon the gasket 95 and secure the joint against leakage. Along the opposite sides of the shell section 10 are pairs of flanges 16 each pair being just far enough apart to allow the division plate 17 to slide freely between, the plate being 100 preferably of copper and placed between the flanges as shown and seated and secured in position with metal cement that will stand water and temperature and harden after the application, the cement not 105 being illustrated because of well known properties and usages.

On the intake side of the division plate 17 is the baffle plate 18 preferably positioned near the upper end of the plate, while near the lower end of the plate 17 is the baffle plate 14, the plates fitting the division plate and

allowing room around the outer edges 20 and 21 respectively, and the shell 10 for circulation, the object of the baffle plates being to break any current or flow of the 5 water that might otherwise occur and compel the water to settle more evenly on the intake side and to rise evenly on the discharge side of the plate 17.

The intake pipe 22 connects from boss 12 10 to the upper side of the generator 1 and to the skimmer 2, while the boss 13 connects through the pipe 23 to the generator 1 at 24 the object being merely to connect from the skimmer near the water line in the 15 generator to any point low down on the generator so that as the water cools passing to and through the precipitator it will increase in gravity and enter the generator through the pipe 24 it being evident that the pressure 20 is constant at equal elevations.

In operation the steam in the generator forces the water through the skimmer and pipe 22 to the precipitator where it is slightly cooled and returned to the generator 25 by gravity.

It is well known that the sediment and properties that are injurious to the interior of the generator are separated from the water as steam is generated and those properties are carried with the steam to the surface of the water within the generator from where they would naturally settle and form incrustations on the inner surface of the generator, but the skimmer provides a discharge for those properties at the point where they are the most numerous and active and they pass to the precipitator, the precipitator being larger and of much greater area than the pipes leading thereto 40 or therefrom the water passes through it slowly and gives the sediment and objectionable properties time to settle within the spherical lower section of shell 3 from where it is discharged from time to time by opening the blowoff valve 25, the cone directs the passage of water or stream along the inner surface of the walls of the cone 7 and removes the sediment immediately whereas if the cone were not provided the water or 45 steam would cut a channel down through the center of the sediment and leave most of it in the shell. It will be understood that if the blowoff valve 25 is opened for a moment the water will be discharged from the intake 50 side of the shell section 10 and steam will be discharged, this often being the result in

cleaning the precipitator. It will also be understood that with steam in the intake side of the shell 10 entering through the boss 12 this side of the shell will be of a much 60 higher temperature than the side next to boss 13, and these variations of temperatures have been found to cause leakage in any kind of joint that has been devised to secure a head to the shell 10, therefore the integral 65 head 11 is of very great importance in the construction of the precipitator. The insertion of the division plate 17 is of especial importance in the construction of the shell 70 as it would not be practical to cast the shell and division wall integral.

The cone 7 allows the sediment to be blown from the shell 3 in a few moments while without the cone the shell is never cleansed even though the valve 25 is opened 75 until the water or steam shows a clean discharge, the saving in heat units lost by cleaning the shell with the cone being considerable over that which is lost without the aid of the cone.

It is obvious that numerous changes may be made in the arrangement of parts and connections without departure from the essentials of the invention.

What I claim as new, and desire to secure 85 by Letters Patent, is:—

1. In a precipitator, a closed cylindrical shell, a division wall extending from the upper end of said shell downward, integral lugs extending into said shell below said 90 division wall, a cone whose largest diameter is smaller than the interior of said shell, said cone supported by said lugs, the vertex of said cone projecting upward, and said vertex being some distance below said division wall.

2. In a precipitator, a closed cylindrical shell, a division wall extending from the upper end of said shell downward, a cone rigidly connected to and supported within 100 said shell, the largest diameter of said cone being smaller than the interior of said shell, the vertex of said cone projecting upward and said vertex being some distance below said division wall.

In testimony whereof I affix my signature in the presence of two witnesses.

JOHN T. WOOLSEY.
